SUBMARINE COMMUNICATION
CONDUCTOR

Victor E. Legg, East Orange, N. J., assignor to
Bell Telephone Laboratories, Incorporated,
New York, N. Y., a corporation of New York

Application March 19, 1929, Serial No. 348,175

5 Claims. (Cl. 173—264)

This invention relates to high frequency submarine cable conductors, more especially designed for transmission of telephony over relatively great distances.

- 5 A fundamental difficulty in long distance submarine cable telephony is the increase of effective resistance of the cable conductor (or conductors in multiple core cables) at frequencies above the range normally used for long distance submarine 10 telegraph service and more especially at the upper end of the telephone frequency range around 2000 cycles per second. For carrier frequencies above 2000 cycles the difficulty is still greater.

The ordinary stranded conductor consisting of 15 a central copper core with several flat strands laid thereabout has a direct current conductivity about 97% of that of solid copper. In such a conductor or in a solid conductor of #4 size (5.189 millimeters in diameter) the resistance is 20 increased about 17.5% at 2000 cycles. This causes a large increase in the attenuation of the cable at such frequencies and is one of the limiting factors in long distance submarine cable telephone communication.

- 25 It has usually been assumed that a braided or stranded conductor composed of fine wires is not suitable for the conductor in such a cable because of its lack of compactness by virtue of which a given amount of copper has a diameter considerably increased as compared to the diameter 30 of a solid or stranded conductor of the ordinary form containing the same amount of copper, which necessitates the use of an increased amount of insulation and an increased 35 amount of armor material. Also the void spaces in such a conductor cause considerable difficulty with the insulating material owing to the fact that if a cable having such void spaces were laid the outside pressure would tend to deform the 40 structure until the void spaces were filled up.

In this specification the term "reentrant type conductor" will be used to include all conductors consisting of a number of small strands braided, twisted or otherwise so laid together that each conductor passes at frequent and regular intervals from the interior to the surface of the conductor. A conductor in which each strand passes regularly and uniformly from the center to the 45 external surface will be termed "symmetrical conductor of the reentrant type".

Experiments have indicated that above a certain frequency (depending upon the size of the conductor) the alternating current resistance 50 loss will be less in a braided or stranded con-

ductor than in a solid conductor of the same physical diameter. For a large conductor such as would be used in a relatively long submarine telephone cable this frequency is about 2500 to 3000 cycles per second. Consequently, a feature of this invention comprises the use of "reentrant type" braided or stranded conductors (sometimes known as Litzendraht for submarine carrier frequency cables).

5 However, also at lower frequencies there may be obtained important advantages in the use of "reentrant type" conductors.

In accordance with another feature of the present invention the void spaces in a conductor of the "reentrant type" are reduced. Experi- 15 ments have indicated that the voids in "reentrant type conductors", in which the separate strands are enameled, may be reduced to such an extent that the conductor has a direct current conductivity equal to 90% of that of solid copper of the 20 same physical diameter and in the case of insulation with metallic oxides still better results may be obtained.

In the case of an ordinary telephone or high frequency cable conductor which is not loaded, 25 the insulation between the strands may consist of a layer or coating on the individual strands of enamel, cellulose acetate or other suitable material.

In the case of a loaded conductor the insulation 30 of each strand may be of a heat resistant material. Alternatively, however, the copper employed may be of a recently developed kind which is deoxidized and does not become reduced and embrittled in the presence of reducing agents at 35 high temperature in which case the insulation need be only sufficiently heat resistant to remain an insulator and may be applied with an organic binder or other material capable of producing reducing gases.

40 A feature of the invention resides in the methods by which a reduction of the voids in a "reentrant type" conductor is accomplished.

Another feature of the invention relates to the manner in which the remaining void spaces are 45 rendered innocuous and relatively unobjectionable.

When refractory insulation upon the individual 50 strands is to be employed it may consist of oxides of copper upon the surface of the strands with or without the application of powdered talc or alundum (Al_2O_3) or of one or a plurality of other refractory oxides or materials. The alundum may be applied in a manner already known in the published patent literature by 55

binding it with glycerol which is boiled off, after the conductor is assembled, by a preliminary heat treatment at about 400° to 500° C. When deoxidized copper is employed the glycerol need not be boiled off.

A particular method of applying a metallic oxide other than copper is to plate the strands with an adherent metal capable of being chemically reduced to an adherent oxide such, for example, as chromium and oxidizing the metal to produce the oxide, for example, in this case, chromium oxide. Another method, which is preferred, is to coat the conductors with copper oxide by ordinary oxidation methods.

It is also within the scope of the invention to plate highly resistive materials directly upon the strands.

The reduction of voids in the conductor may be accomplished by drawing, swaging, rolling or by a combination of these methods.

Suitable results may be obtained by drawing the conductor through a series of devices each consisting of grooved opposing wheels free to rotate, each successive device having a space between the rollers smaller than the preceding and that of the final being equal to the diameter to which the conductor is to be reduced.

An unloaded conductor for carrier current cables may be employed without the application of mechanical force to reduce the diameter. In such case, the conductor is impregnated with a liquid bituminous material, Chatterton's compound or melted rubber, to fill up the void spaces. This may be accomplished by running the conductor through a vacuum and thence directly into an extruding machine containing such filling material under pressure.

If the conductor is to be magnetically loaded, it will ordinarily be reduced in diameter by mechanical force suitably applied and then the magnetic material will be applied. After this the loaded conductor will be heat treated in one of the several manners well known in the art. In such a case, of course, only a conductor having heat resistant insulation material on the strands may be employed. In the case of a loaded conductor the impregnating material is applied in such a manner as to function also as a pressure equalizing substance for the magnetic material and a suitable thin layer a few thousandths of an inch thick is left upon the outer surface of the magnetic material for this purpose.

Gutta percha or similar insulating material is applied in the usual manner to form a core which may be used in a single conductor cable or in a twin or other multiple conductor cable.

In a particular case enameled deoxidized #16 (B & S gauge) copper conductors were doubled, twisted, redoubled and retwisted until a conductor of 16 strands was formed. This conductor was run through a swaging machine. The copper content, as indicated by the direct current resistance, was about 90% that of solid copper as compared to about 97% in the case of a stranded conductor of the ordinary type. The increased resistance, however, is more than counterbalanced at a relatively low frequency. In another case 27 strands of #16 enameled wire were braided. This conductor was drawn through a die which reduced it to a cross-section of 300 mils and a length swaged to 239 mils for measurements. As compared with solid copper this conductor had 87% copper content. Alternating current resistance measurements indicated that the inefficiency due to the increased direct current

resistance would be counteracted above a relatively low frequency.

Another way of preparing a "symmetrical conductor of the reentrant type" is to twist together three small wires and then twist together three strands of the resultant wires and continue twisting three by three until a 27- or 81-strand conductor is formed. In such a conductor each strand occupies the same relatively distant position measured from the central conductor as any other strand.

The invention is not limited in application to telephony or high carrier frequencies but may be employed for telegraph cables operating on frequencies in the voice range or higher. The unloaded "reentrant type" conductor may be employed in a coil loaded cable.

In the accompanying drawing:

Fig. 1 is a cross section of a core having an unloaded conductor of the "reentrant type" not reduced in diameter by mechanical force;

Fig. 2 is a cross section of a core having an unloaded conductor of reduced diameter;

Fig. 3 is a cross section of a core including a tape loaded conductor; and

Fig. 4 is a view of the cable core of Fig. 3 having the various parts cut away for inspection of the next inner portion.

None of the figures are intended to be drawn to show relative dimensions.

In Fig. 1 the core comprises a conductor having strands 1 with an enamel coating 4a each passing from the central to the external portion of the conductor, a bituminous filler 2, between the strands and a layer 3 of insulation.

Fig. 2 is an attempt to show the irregular cross-sectional shapes taken at a particular point by the strands 1 under the influence of a swaging process. The layer of oxide 4 appears disproportionately thick. Drafting technique does not make it feasible to show in the various figures the semi-liquid filler between the strands or the spaces it occupies, except around the exterior of the strands at 2. Insulation 3 is of known type such as gutta percha.

In Figs. 3 and 4, in addition to the strands 1 of the swaged conductor, filler 2, coating 4 and insulation 3, the loading tape 5 is shown surrounded by an excess portion 6 of filler material functioning as a pressure equalizing substance.

What is claimed is:

1. The method of manufacturing a many stranded conductor of the "reentrant type" which comprises applying a metallic oxide to the strands, laying the strands together by a braiding or twisting operation which causes each strand to be reentrant and reducing the void spaces by the application of mechanical force of the type including rolling, swaging and drawing.

2. The method of manufacturing a conductor for a deep sea signaling cable which comprises lightly insulating a plurality of strands, spirally laying a plurality of said strands together to form composite strands, and spirally laying a plurality of said composite strands together; and thereafter reducing the void spaces in the resulting structure by the application of mechanical force of the type including rolling, swaging and drawing.

3. A deep sea high frequency signaling cable having a principal conductor which is a many stranded conductor of the "reentrant type" having its void spaces filled with impregnating material in which the "reentrant type" conductor is

of reduced diameter as by swaging and is composed of insulated strands, the whole being impregnated with material of the class including Chatterton's compound, bitumen and melted rubber to completely fill the residual voids and insulated with thermoplastic material.

4. A deep sea signaling cable having a principal conductor which is a many stranded conductor of the "reentrant type" forcibly compressed and having its void spaces filled with impregnating material having between the strands an insulating material which is heat-resistant and a magnetic

material applied about the conductor for the purpose of increasing the inductance thereof.

5. A deep sea signaling cable having a principal conductor which is a many stranded conductor of the "reentrant type" having its void spaces filled with impregnating material in which the individual strands forming the conductor lie compactly together and have generally polygonal cross-sections whereby the void spaces are reduced to a minimum.
